UNITED STATES PATENT OFFICE.

WILLIS G. RIDGE, OF NEW HAVEN, CONNECTICUT, ASSIGNOR OF ONE-HALF
TO CLIFFORD A. HILDRETH, OF SAME PLACE.

PIPE-CO尤LING FOR RAILWAY-CARS.

SPECIFICATION forming part of Letters Patent No. 448,261, dated March 17, 1891.

Application filed January 26, 1891. Serial No. 379,065. (No model.)

To all whom it may concern:

Be it known that I, WILLIS G. RIDGE, of New Haven, in the county of New Haven and State of Connecticut, have invented a new Improvement 5 in Pipe-Couplings for Railway-Cars; and I do hereby declare the following, when taken in connection with accompanying drawings and the letters of reference marked thereon, to be a full, clear, and exact description of 10 the same, and which said drawings constitute part of this specification, and represent, in—

Figure 1, a view in side elevation of one member of a coupling device embodying my invention; Fig. 2, a similar view showing two 15 of such members coupled together, the inner end of the sleeve of the coupling-head of the left-hand member being broken away; Fig. 3, a detached view in side elevation of so much of the coupling-head of the left-hand member 20 as is shown in Fig. 2 of the drawings; Fig. 4, a view in vertical transverse section on line *a b* of Fig. 2, showing the two coupling-heads in position for locking; Fig. 5, a similar view showing them after they have been rotated 25 and locked; Fig. 6, a broken view in vertical longitudinal section of one member, drawn on a larger scale than in the preceding figures; Fig. 7, a view in end elevation of the said member, drawn on the same scale and with 30 its coupling-arms in section. Fig. 8 is a detached face view of the buffer with the packing and retaining-rings removed. Fig. 9 is a similar view of the retaining-ring.

My invention relates to an improvement in 35 coupling devices for the steam and compressed-air pipes of railway-cars, the object being to provide for the automatic coupling and uncoupling of the said pipes in a construction which shall be at once simple, compact, durable, and reliable.

With these ends in view my invention consists in certain details of construction and combinations of parts, as will be hereinafter described, and pointed out in the claims.

45 Inasmuch as the two members of my improved coupling device are alike, a description of one will suffice for both.

Each is provided with a supporting-pipe *A*, having its inner end mounted in a head *B*, 50 pivotally connected with a hanger *C*, which

is suspended beneath and flexibly connected with the car to which the member is applied in line with the longitudinal center thereof. The outer end of the said supporting-pipe has sleeved over it the inner end of a sleeve *D*, 55 which is provided at its outer end with two projecting coupling-arms *E* and *E'*, having diverging tapering terminations, so that in case they should happen to be exactly in line with the corresponding arms of the co-operating member when the cars come together the arms of the two members would not engage and break, but glance off from each other and come together properly in position for being interlocked. The said arm *E* is provided about midway of its length with a transverse slot *F*, having its outer wall beveled, as at *F'*, while the arm *E'* is provided near its inner end with a transverse tapering finger *F'*, curved to conform to the curvature of the 70 sleeve *D*.

For convenience of identification I shall hereinafter refer to the arm provided with the slot as the "slotted arm" and the arm provided with the curved finger as the "finger-arm." By reference to Fig. 7 of the drawings it will be seen that the said arms are not located directly opposite each other, but that the finger-arm is slightly set back from the position which it would occupy if it were in 8 line with the slotted arm. The object of this construction is to bring the slotted arms of the respective members in line when the members are coupled, as shown by Fig. 5 of the drawings, so as to have the strain tending to pull the two members apart equally divided between the two slotted arms. The said sleeve *D* is provided at opposite points with two longitudinal slots *D'*, having straight forward ends and offsetting rear ends, the latter extending in the same direction. These slots respectively receive pins *A' A'*, mounted in the supporting-pipe *A*, and co-operating to guide the sleeve and to impart rotal movement thereto when the same approaches the limit of its longitudinal inward movement. This rotal movement of the sleeve may be more or less according to the particular construction of the coupling device; but as herein shown the slots are designed to impart rotal

movement to the sleeve through one-eighth of the circumference of a circle.

A spiral spring G, encircling the supporting-pipe A and the inner end of the sleeve D, is interposed between the head B and a guy-plate H, loosely mounted upon the sleeve and set against an annular flange D², formed near the outer end thereof, the said spring exerting a constant effort to push the sleeve outward and having the additional function of aiding the coupling-arms in maintaining a steam and air tight connection between the two members of the device when they are interlocked.

15 For convenience I shall hereinafter refer to the sleeve and its adjuncts as the "coupling-head" of a coupling member.

A steam-pipe I and a concentric air-pipe J extend throughout the length of the supporting-pipe and coupling-head, with which, however, they have no positive connection. The outer ends of the said pipes are connected together by an annular flanged buffer K, which projects slightly beyond the outer end of the sleeve. This buffer is constructed with a central passage K', located in line with the steam-pipe I, and with four passages K², located in line with the air-pipe J, the said pipes I and J being threaded into the inner end of the buffer. A spiral spring L of few coils is interposed between the inner end of the buffer and an inwardly-projecting flange D³, formed in the outer end of the sleeve D, and provides a yielding cushion for the buffer, which extends sufficiently beyond the outer end of the sleeve to have a slight longitudinal movement therein and to compensate for wear, the extreme limit of play in the buffer being represented by the space N shown in Fig. 6 of the drawings.

Two packing-rings O and P, of rubber or equivalent material, are applied to the outer face of the buffer, and are engaged by corresponding rings on the other member of the device to form a tight joint between the two coupling members. These rings are provided with inwardly-projecting flanges O' and P', which fit into an annular groove Q, formed in the outer face of the buffer and having tapering walls. The said flanges are engaged for holding the rings in place by means of a retaining-ring R, having flaring edges and secured in the bottom of the said groove by means of screws R', which enter the webs S formed between the passages K' in the buffer. The retaining-ring is constructed with passages R², corresponding to the passages K², with webs R³, corresponding to the webs S of the buffer, and with a central opening R⁴, corresponding to the central passages K' of the buffer, whereby the ring does not interfere with the passage of steam and air from one coupling member to the other.

The inner end of the air-pipe J is closed by means of a collar J', which encircles the steam-pipe I, the said air-pipe being provided with a flexible supply-pipe J², connected with any

convenient source of compressed-air supply. The inner end of the steam-pipe I has a flexible connection, which is not shown, with any suitable source of steam-supply.

The outer end of each coupling member is supported by the horizontal guy-plate H, before referred to, the said plate being provided at its opposite ends with perforations H', to which yielding guys, preferably in the form of springs and not shown herein, are connected.

Having fully described my invention in detail, I will now proceed to set forth the mode of its operation.

One of the coupling members is applied to each end of every car. Now when two cars are brought together for coupling, the outer ends of the projecting coupling-arms of the respective coupling-heads will first pass each other and permit the buffers of the two coupling-heads to engage with each other. Then as the cars approach nearer the coupling-heads of the respective members will be pushed back against the tension of their spiral operating-springs, and as they move back they will be rotated by the co-operation of the offsetting ends of the slots in their sleeves with the pins in the supporting-pipes of the members. As the heads are rotated the finger of the finger-arm of one head will be shot into the transverse slot of the slotted arm of the other head, and vice versa, whereby the heads of the two members are coupled together. As the coupling-heads are rotated, as described, the beveled outer walls of the transverse slots in the slotted arms assist in drawing the packing-rings of the two members into closer contact, and the coupling thus established is reinforced by the operating-springs G G and the buffer-springs L L of the two members. After the described coupling of the two heads has taken place they are pushed still farther inward before the cars are coupled, and until the pins are well cleared from the offsetting portions of the slots and brought into the straight portions thereof, in which they are free to play back and forth within the limits required to accommodate the coupling thus established to those slight changes constantly occurring in the relative longitudinal positions of the cars when the same are in motion. When the cars are uncoupled and separated, the said operating-springs at once push the coupling-heads outward and again bring the offsetting ends of their slots into range with the said pins, whereby the heads are reversely rotated and uncoupled, after which they are free to separate when the cars move apart. It will thus be seen that by means of my improvement the steam and compressed-air pipes of two adjacent cars are automatically coupled and uncoupled.

The particular devices for suspending the coupling members and for connecting their steam and air pipes with sources of steam and compressed-air supply may be varied as desired. The particular construction of the

couplers may also be modified. For instance, it is not necessary that both of the coupling-heads of two co-operating coupling members should be made to rotate, although it is desirable that both should rotate on account of the convenience it offers. I would therefore have it understood that I do not limit myself to the exact construction shown and described, but hold myself at liberty to make such changes and alterations as fairly fall within the spirit and scope of my invention.

Having fully described my invention, what I claim as new, and desire to secure by Letters Patent, is—

- 15 1. In a coupler for the steam and compressed-air pipes of railway-cars, a supporting-pipe, means for suspending the inner end thereof, a sleeve mounted upon its outer end so as to rotate when moved inward upon the same and provided at its outer end with two coupling - arms having diverging tapering ends, one being provided with a transverse slot and the other with a transverse finger, a steam-pipe extending throughout the length 25 of the said operating-pipe and sleeve, an air-pipe concentric with the steam-pipe, a buffer connecting the outer ends of the steam and air pipes and projecting beyond the outer end of the sleeve, and steam and air connections 30 with the inner ends of the steam and air pipes, substantially as described.
2. In a coupler for the steam and compressed-air pipes of railway-cars, a supporting-pipe, a sleeve mounted upon the outer end thereof and provided with longitudinal slots, pins mounted in the pipe and entering the said slots, which are shaped to co-operate with the pins in causing the sleeve to rotate, and two coupling-arms projecting from the outer end 40 of the sleeve and having tapering extremities, one of the said arms being provided with a transverse slot and the other with a transverse finger, substantially as described.
3. In a coupler for the steam and compressed-air pipes of railway-cars, the combination, with a pipe and a sleeve rotably and longitudinally movable thereupon and provided at its outer ends with two projecting coupling-arms having diverging tapering ends and respectively constructed with a transverse slot and provided with a transverse finger, of yielding supports for the said pipe and sleeve, concentric steam and air pipes located within the sleeve and supporting-pipe, and an annular

55 buffer connecting the outer ends of the steam and air pipes, projecting beyond the outer end of the sleeve, and provided upon its outer face with packing-rings, substantially as described.

4. In a coupler for the steam and compressed-air pipes of railway-cars, the combination, 60 with a pipe and a rotal and reciprocal sleeve mounted thereupon and provided at its outer end with two projecting coupling-arms, of concentric steam and air pipes extending throughout the length of the said pipe and 65 sleeve, a flanged annular buffer connecting the outer ends of the pipes, projecting beyond the outer end of the sleeve, constructed with passages in line with the said pipes, and provided with packing-rings applied to its outer 70 face, and a spring combined with the sleeve and buffer and located within the former for providing a yielding bearing for the latter, substantially as described.

5. In a car-coupler, the combination, with a 75 supporting-pipe and a rotal and reciprocal sleeve mounted thereupon and having two projecting coupling-arms, of concentric steam and air pipes located within the said pipe and sleeve, an annular buffer connecting the outer 80 ends of the steam and air pipes and having openings in line with the same, an annular groove which is formed in its outer face, two concentric packing-rings applied to the face of the buffer and having flanges which 85 enter the said groove, and a flaring retaining-ring having passages in line with the said steam and air pipes located in the groove for holding the flanges of the packing - ring 90 therein, substantially as described. 95

6. In a car-coupler, the combination, with two coupling members, each having a supporting-sleeve, and a rotal and reciprocal coupling-head, of concentric steam and air pipes located within the said pipe and head, a buffer 95 projecting beyond the head and connecting the outer ends of the pipes, and means for supporting the said member so that they will yield to the relative movements of the cars to which they are applied, substantially as described. 100

In testimony whereof I have signed this specification in the presence of two subscribing witnesses.
